Patented Feb. 1, 1966

203,630

COMBINED LITTER CONTAINER AND TISSUE DISPENSER

Thomas E. Wright, 6862 Lode Drive, Worth, Ill.

Filed Feb. 23, 1965, Ser. No. 83,917

Term of patent 14 years

(Cl. D58—17)

Fig. 1

Fig. 2

Fig. 3

Fig. 4

FIGURE 1 is a perspective view of a combined litter container and tissue dispenser, showing my new design; FIG. 2 is a front view of the same;

FIG. 3 is a side view of the same, looking at the right-hand side of FIG. 2;

FIG. 4 is a perspective view of the same, looking from the bottom, rear, and side opposite from that shown in FIG. 3; and

FIG. 5 is a top plan view of the same, from the position shown in FIG. 1.

I claim:

The ornamental design for a combined litter container and tissue dispenser, substantially as shown and described.
